CLAIM

The ornamental design for a laboratory apparatus as shown and described.

DESCRIPTION

The file of this patent contains at least one drawing/photograph executed in color. Copies of this patent with color drawing(s)/photograph(s) will be provided by the Office upon request and payment of the necessary fee.

1. Laboratory apparatus

1.1 : Front View—in rest position

1.2 : Right View—in rest position

1.3 : Left View—in rest position

1.4 : Right Perspective View—in rest position

1.5 : Left Perspective View—in rest position

1.6 : Right Perspective View—in tips grip position

1.7 : Left Perspective View—in tips grip position

1.8 : Back View—in rest position

1.9 : Bottom View—in rest position

1.10 : Top View—in rest position

1 Claim, 10 Drawing Sheets
(10 of 10 Drawing Sheet(s) Filed in Color)
